PATENTED DEC. 24, 1907.

C. DELCAMPE.

BLOWPIPE.

APPLICATION FILED MAR. 13, 1907.

UNITED STATES PATENT OFFICE.

CYRILLE DELCAMPE, OF QUINCY, MASSACHUSETTS.

BLOWPIPE.

No. 874,492.

Specification of Letters Patent.

Patented Dec. 24, 1907.

Application filed March 13, 1907. Serial No. 362,230.

To all whom it may concern:

Be it known that I, CYRILLE DELCAMPE, a subject of the King of Belgium, residing at Quincy, in the county of Norfolk and State 5 of Massachusetts, have invented certain new and useful Improvements in Blowpipes; and I do hereby declare the following to be a full, clear, and exact description of the invention, such as will enable others skilled in the art to 10 which it appertains to make and use the same.

My invention relates to improvements in blow-pipes adapted to mix and burn a combustible gas and a gas which supports combustion. It has found its practical embodiment in a blow-pipe particularly designed to 15 use acetylene and oxygen.

The construction and operation of my improved blow-pipe will be understood from 20 the accompanying drawings, taken in connection with the following description.

In the drawing, Figure 1 is an elevation, partly in section, of the complete blow-pipe; Fig. 2 is a central section of the head of the 25 blow-pipe on an enlarged scale, and Fig. 3 is a section on the line 3—3 of Fig. 1.

The blow-pipe comprises an acetylene pipe A and an oxygen pipe B, the exit end of the oxygen pipe being arranged within the exit 30 end of the acetylene pipe which forms the blow-pipe head. Secured to the upper end of the pipe A is an elbow a terminating in the cylindrical enlargement b. The elbow is provided at the turn with an opening, through 35 which the upper end of the oxygen pipe B passes. Secured to the end of the pipe B within the cylindrical enlargement of the elbow a is a flanged collar c screw-threaded on its inside and outside, as shown. The screw-

40 threads on the inside are intended to take a screw-threaded oxygen injector nozzle d and the screw-threads on the outside are intended to take the cylindrical chimney e provided with the holes e'. These holes or passages e'

45 are arranged in a circle and are located in the chimney e forward of the exit end of the injector nozzle d and their direction is at right-angles to the direction of flow of the gas from the injector nozzle. By this arrangement 50 the jets of gas from the holes e' converge directly in the path of the gas from the injector nozzle d and an intimate mixture of the gases is secured. The holes or passages e' are, moreover, contracted as they approach the

55 inside of the chimney, as shown more clearly in Fig. 2, for the purpose of giving the desired

velocity to the acetylene jets passing through them and preventing the flashing back of the flame into the chamber outside of the chimney. Screwed into the cylindrical enlargement b of the elbow a is the plug f, containing a cylindrical gas chamber of somewhat greater diameter than the chimney e. The diameter of this cylindrical chamber is reduced near the forward end of the plug to 60 form a shoulder against which the end of the chimney e rests and the chamber is continued beyond the shoulder as the relatively contracted chamber f' forming the mixing chamber and into the forward end of which the 65 main nozzle g is screwed.

The acetylene pipe A is connected by a suitable detachable coupling A' to the pipe A² running through a cylindrical sheathing D. The coupling A' is provided on its inside 75 with a plurality of layers of gauze, as shown, to prevent back firing, and the pipe A² terminates outside of the sheathing D in a plug h having a turn-cock h'. The pipe B is connected by the detachable coupling B' to the 80 pipe B², which also passes through the sheathing D and terminates at its lower end in the plug m having a turn-cock m'. To detach the pipes A and B from the handle D in order to inspect and repair the wire gauzes, etc., 85 the detachable couplings B' and A' are unscrewed, as will be understood. The pipe B is bent away from the pipe A, but secured in proximity thereto by the clip E, the pipe being sufficiently resilient to press the front 90 end of the chimney e into contact with the shoulder within the plug f. The cylindrical sheathing D serves as a handle for the blow-pipe.

When it is desired to use the blow-pipe so 95 constructed, an injector nozzle d and a main nozzle g are selected (from sets of nozzles kept for that purpose) of a fixed relative capacity, such as to give the proper mixture of oxygen and acetylene at a definite pressure. The 100 oxygen supply is maintained under a greater pressure than the acetylene supply and when the cocks m' and h' are opened, the oxygen rushing through the injector nozzle d meets the entering jets of acetylene in the manner 105 above described and the mixed gases flow at a high velocity through the main nozzle g. If it is desired to change the size of the flame, both the main nozzle and the injector nozzle are removed, and other nozzles of different 110 capacity, but bearing the same definite relation to one another, are substituted. It re-

sults from this that when the flame is to be started it is only necessary to open fully the cocks m' and n' and light the mixed gases issuing from the nozzle g , and a flame of the 5 desired size and of great impinging force is at once secured, and it is moreover unnecessary to search for the proper mixture of acetylene and oxygen by adjusting regulating valves, since at a definite pressure the proper mixture 10 of acetylene and oxygen results from the relation between the main and injector nozzles and the acetylene orifices e' in the chimney e .

In practice, each blow-pipe is provided 15 with a set of main nozzles and a set of injector nozzles of corresponding relative capacity properly calibrated for a definite pressure and marked with suitable reference characters.

What I claim is:—

20 1. In a blow-pipe to which a combustible gas and a gaseous supporter of combustion are supplied under pressure, a gas supply pipe terminating in a head containing a mixing chamber, a detachable main nozzle in 25 said head forming an outlet from the mixing chamber and a second gas supply pipe terminating in said head and provided with a detachable injector nozzle of a definite capacity with relation to the main nozzle and which 30 discharges directly into the mixing chamber, whereby when it is desired to change the size of the flame both detachable nozzles may be removed and replaced by other nozzles of different capacity, but having the same 35 definite relation, substantially as described.

2. In a blow-pipe, a gas supply pipe terminating in a head containing a gas chamber and a mixing chamber, a detachable main nozzle in said head forming an outlet from 40 the mixing chamber, a partition in said head between the gas chamber and mixing chamber, gas ports in said partition, and a second gas supply pipe terminating in said head and provided with a detachable injector nozzle 45 having a definite capacity with relation to the main nozzle and which discharges into the mixing chamber, whereby when it is desired to change the size of the flame both detachable nozzles may be removed and replaced 50 by other nozzles of different capacity but having the same definite relation, substantially as described.

3. In a blow-pipe, a gas supply pipe terminating in a head containing a gas chamber 55 and a mixing chamber, a detachable main nozzle in said head forming an outlet from the mixing chamber, a second gas pipe extending into said head and terminating in a nozzle support, a detachable injector nozzle 60 in said support of a definite capacity with relation to the main nozzle, a chimney surrounding said injector nozzle and forming a partition between the gas chamber and the mixing chamber, and gas ports in said chimney, whereby when it is desired to change the 65

size of the flame both detachable nozzles may be removed and replaced by other nozzles of different capacity but having the same definite relation, substantially as described.

4. In a blow-pipe, a gas supply pipe terminating in a head containing a gas chamber and a mixing chamber, a nozzle in said head forming an outlet from the mixing chamber, a partition in said head between the gas chamber and the mixing chamber, gas ports in 70 said partition, and a second gas supply pipe terminating in said head and provided with an injector nozzle which discharges into the mixing chamber, the partition and the injector nozzle being so constructed and arranged that the direction of flow from the gas ports in the partition is at right angles to the direction of flow from the injector nozzle, whereby an intimate mixture of the gases is secured, substantially as described. 85

5. In a blow-pipe, a gas supply pipe terminating in a head containing a gas chamber and a mixing chamber, a nozzle in said head forming an outlet from the mixing chamber, 90 a partition in said head between the gas chamber and mixing chamber, gas ports in said partition having a progressively reduced diameter from the gas chamber toward the mixing chamber, and a second gas supply pipe terminating in said head and provided with an injector nozzle which discharges into the mixing chamber, whereby the flashing back of the flame into the gas chamber is prevented, substantially as described. 95

6. In a blow-pipe, a gas supply pipe terminating in a head containing a gas chamber and a mixing chamber, a nozzle in said head forming an outlet from the mixing chamber, a second gas supply pipe extending into said 105 head and terminating in a nozzle support, a nozzle in said support, a chimney surrounding said nozzle and forming a partition between the gas chamber and the mixing chamber, and a circular series of gas ports in said chimney forward of the said nozzle and having a progressively reduced diameter from the gas chamber toward the mixing chamber, substantially as described. 110

7. In a blow-pipe, a gas pipe terminating in 115 a head containing a gas chamber, a shoulder, a mixing chamber beyond the shoulder, and a nozzle forming an outlet from the mixing chamber, a second gas pipe entering said head and carrying on its free end a chimney 120 adapted to rest with its open end against the shoulder in the head and form a partition between the gas and mixing chambers, and gas ports in said chimney, substantially as described. 125

8. In a blow-pipe, a gas pipe terminating in a head containing a gas chamber, a shoulder, a mixing chamber beyond the shoulder, and a nozzle forming an outlet from the mixing chamber, a second resilient gas pipe en- 130

tering said head and carrying on its free end a nozzle and a chimney surrounding said nozzle, the open end of said chimney being forced by the resiliency of the pipe against the shoulder in the head to form a partition between the gas chamber and the mixing chamber, and gas ports in said chimney, substantially as described.

9. In a blow-pipe, a gas pipe terminating in a head containing a gas chamber, a shoulder, a mixing chamber beyond the shoulder, and a nozzle forming an outlet from the mixing chamber, a second resilient gas pipe supported in proximity to the first pipe but bent outwardly therefrom, a clip on the first pipe engaging the second pipe, the free end of the second pipe entering the head and carrying a nozzle and a chimney surrounding the nozzle, the open end of the said chimney being forced by the resiliency of the pipe against the shoulder in the head to form a partition between the gas chamber and the mixing chamber, and gas ports in said chimney, substantially as described.

25 10. In a blow-pipe, a head containing a gas chamber and a mixing chamber, a nozzle

in said head forming an outlet from the mixing chamber, a partition in said head between the gas chamber and mixing chamber, gas ports in said partition, and a second gas supply pipe terminating in said head and provided with an injector nozzle which discharges into the mixing chamber, substantially as described.

11. In a blow-pipe, a gas supply pipe terminating in a head containing a gas chamber and a mixing chamber, a nozzle in said head forming an outlet from the mixing chamber, a second gas supply pipe extending into said head and terminating in a nozzle support, an injector nozzle in said support, a chimney surrounding said nozzle and forming a partition between the gas chamber and the mixing chamber, and gas ports in said chimney, substantially as described.

45 In testimony whereof I affix my signature, in presence of two witnesses.
